UNITED STATES PATENT OFFICE

MORRIS C. YEAMAN, OF PONCA CITY, OKLAHOMA

HYDRAULIC ROTARY DRILLING BIT

Application filed March 7, 1931. Serial No. 520,893.

This invention relates to certain new and useful improvements in hydraulic rotary drilling bits.

The primary object of the invention is to provide a hydraulic rotary drilling bit especially designed for the drilling of prospect holes for testing underlaying formations below the surface of the earth for oil, gas and mineral products, the drilling bit embodying an impeller or turbine wheel operatively engaged with a cutter head with exhaust passages through the bit body for the escape of the impelling fluid.

A further object of the invention is to provide a hydraulic rotary drilling bit of the foregoing character wherein the passageways in the bit body for the impelling fluid include removable tubular wear surfaces so that permanent parts of the bit body are protected from erosion.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of a hydraulic rotary drilling bit constructed in accordance with the present invention, showing the cutter head at the lower end of the bit body and the side reamer;

Figure 2 is a vertical longitudinal sectional view of the drilling bit;

Figure 3 is a horizontal sectional view taken on line 3—3 of Figure 1, showing the diametrically disposed reamers;

Figure 4 is a vertical cross-sectional view of the head of the bit body;

Figure 5 is a bottom plan view of the cutter head; and

Figure 6 is a top plan view of the impeller or turbine wheel for driving the cutter head.

The drilling bit comprises a cylindrical body 10 housing the operating mechanism for the cutter head 11 located exteriorly of the lower end thereof, the upper end of the body 10 being provided with an annular pocket 12,

the wall of which is internally threaded as at 13 to receive the externally threaded flange 14 depending from the head 15 which is of frusto-conical formation, an externally threaded collar 16 rising from the head 15 to 55 which a drill pipe or stem is attached. The head 15 has a cross piece 17 therein forming the top wall of a cross passage 18 outletting at each side of the head as at 18° as shown in Figure 2, the cross piece 17 as shown in Figure 4 being disposed between lateral inclined passages 19 terminating in outlets 20 at the lower end of the head 15 at points spaced 90° from the outlets 18a, the opening 18 communicating with a central bearing passage 60 21 in the base of the head 15 as illustrated.

The pocket 12 in the bit body 10 has an annular shoulder 22 formed in the lower end thereof that extends transversely of the body and upon which an impeller case 23 is mounted, the case having an exterior screw threaded connection with the threads 13 upon the wall of the pocket 12, while an axial bore 24 in the impeller case provides bearings for the tubular drive shaft 25, the bore of the impeller case having a ring gasket 26 set therein engaged with the tubular drive shaft. An annular tapering pocket 27 is provided in the impeller case 23, the upper end of the inner wall of the pocket being cut away and spaced 70 80 from the lower end of the head flange 14, while the outer wall of the pocket or case extends upwardly for engagement with the lower edge of the head flange. A turbine wheel or impeller 28 has the central hub portion thereof internally threaded as at 29 to be engaged with the screw threaded portion 30 of the tubular drive shaft 25, the latter extending upwardly into the passage opening 75 85 90 95 100 21 in the head 15 as shown in Figure 2. Inclined tapering blades 31 are carried by the impeller hub 28 and occupy the inclined annular pocket 27 in the impeller case 23. Roller bearings 32 are interposed between the tubular drive shaft 25 and the wall 33 of the bit body 10 in spaced relation to each other and below the impeller case 23, being retained in position by retaining rings 34 and 35, the retaining rings 34 and 35 carrying

packing rings and gaskets to protect the bearings from the motive fluid.

The cutter head 11 has an axial opening therein that is internally threaded for the reception of the threaded end 36 of the tubular drive shaft 25 that projects below the bit body 10, the cutter head carrying retaining members 37 for the ring 35. The lower face of the cutter head 11 is of conical form and is 10 provided with radial cutting teeth 38 extending over the entire face thereof and merging at their outer ends into an annular group of cutting teeth 39.

A pair of diametrically arranged longitudinally extending passages 40 are provided in the drill body 10 and in which renewable linings 41 are positioned, said linings being in the form of pipes that have their upper ends threaded for reception in openings provided in the lower end of the case 28 as shown at 42, the pipes 41 communicating with the annular pocket 27 in the impeller case, while the lower ends of the pipes 41 register with openings 43 provided in the cutter head 11 20 during rotation of the latter. Diametrically opposite reamers 44 are set into side openings 45 provided in the bit body 10 and operate to cut a clearance for the drill body 10 and cutter head 11 when the peripheral teeth 39 25 of the cutter head become slightly worn. A pipe lining 46 is provided for tubular drive shaft 25 providing a wear surface for the drive shaft against erosion, the pipe lining 46 having threaded engagement at its upper end with the tubular drive shaft as illustrated in Figure 2.

In the operation of the drilling bit, motive fluid under pressure of a slush pump located on the surface of the earth is delivered 40 through a drill pipe or stem to the collar 16 of the bit head 15 to flow through the openings 19 and 20 in contact with the inclined blades 31 of the impeller 28, the impeller being attached to the tubular drive shaft 25 for 45 communicating rotary motion to the cutter head 11. The motive fluid exhausts through the pipe linings 41 in the passages 40 during each quarter revolution of the impeller and through the outlets 43 when the latter are rotatably moved into communication with the exhaust passages, the motive fluid washing over the cutter head teeth 38 and 39 for cleaning the same, a part of the fluid rising to the surface of the earth outwardly of the bit body 10 while another part of the motive fluid rises through the pipe lining 46 for the tubular drive shaft 25 to exhaust through the lateral ports 18 and 18a and rising to the surface of the earth. The roller bearings 32 55 are well protected from the motive fluid and those surfaces of the bit body which are subjected to erosion by contact with the motive fluid are provided with renewable faces, such as the pipe linings 41 and 46 which are 60 easily removable and replaceable.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:

1. In a hydraulic rotary drilling bit of the character described, a cylindrical bit body, a tubular shaft journalled therethrough and constituting an upward exhaust for motive fluid, a rotary impeller fixed to the upper end of the shaft within the bit body, and a cutter head fixed to the lower end of the shaft exteriorly of the body.

2. In a hydraulic rotary drilling bit of the character described, a cylindrical bit body, a tubular shaft journalled therethrough and constituting an upward exhaust for motive fluid, a rotary impeller fixed to the upper end of the shaft within the bit body, and a cutter head fixed to the lower end of the shaft exteriorly of the body, the bit body having motive fluid exhaust passages therein laterally of the tubular shaft and renewable pipe linings for the passages.

3. In a hydraulic rotary drilling bit of the character described, a cylindrical bit body, a tubular shaft journalled therethrough and constituting an upward exhaust for motive fluid, a rotary impeller fixed to the upper end of the shaft within the bit body, and a cutter head fixed to the lower end of the shaft exteriorly of the body, the bit body having motive fluid exhaust passages therein extending from the lower end of the impeller to the lower end of the bit body and laterally of the tubular shaft and renewable pipe linings for the passages.

4. In a hydraulic rotary drilling bit of the character described, a cylindrical bit body, a tubular shaft journalled therethrough, a rotary impeller fixed to the upper end of the shaft within the bit body, a cutter head fixed to the lower end of the shaft exteriorly of the body, the impeller including a case secured in the bit body having a V-shaped annular pocket therein, and the blades of the propeller being of V-shape and inclined and moving through the annular pocket.

5. In a hydraulic rotary drilling bit of the character described, a cylindrical bit body, a tubular shaft journalled therethrough, a rotary impeller fixed to the upper end of the shaft within the bit body, a cutter head fixed to the lower end of the shaft exteriorly of the body, the bit body having motive fluid exhaust passages therein and renewable pipe linings for the passages, the impeller including a case secured in the bit body having a V-shaped annular pocket therein, and the blades of the propeller being of V-shape and in-

clined and moving through the annular pocket.

6. In a hydraulic rotary drilling bit of the character described, a cylindrical bit body, a tubular shaft journaled therethrough, a rotary impeller fixed to the upper end of the shaft within the bit body, a cutter head fixed to the lower end of the shaft exteriorly of the body, the bit body having motive fluid exhaust passages therein extending from the lower end of the impeller to the lower end of the bit body and renewable pipe linings for the passages, the impeller including a case secured in the pit body having a V-shaped annular pocket therein, and the blades of the propeller being of V-shape and inclined and moving through the annular pocket.

7. In a hydraulic rotary drilling bit of the character described, a cylindrical bit body, a tubular shaft journaled therethrough, a rotary impeller fixed to the upper end of the shaft within the bit body, and a cutter head fixed to the lower end of the shaft exteriorly of the body, the bit body having motive fluid exhaust passages therein and renewable pipe linings for the passages, the supply passages for the motive fluid being in communication with the impeller and other passages in the bit body being in communication with the upper end of the tubular shaft and forming outlets from the bit body for the motive fluid flowing upwardly through the tubular shaft.

8. In a hydraulic rotary drilling bit of the character described, a cylindrical bit body, a tubular shaft journaled therethrough, a rotary impeller fixed to the upper end of the shaft within the bit body, and a cutter head fixed to the lower end of the shaft exteriorly of the body, the bit body having motive fluid exhaust passages therein extending from the lower end of the impeller to the lower end of the bit body and renewable pipe linings for the passages, the supply passages for the motive fluid being in communication with the impeller and other passages in the bit body being in communication with the upper end of the tubular shaft and forming outlets from the bit body for the motive fluid flowing upwardly through the tubular shaft.

In testimony whereof I affix my signature.
MORRIS C. YEAMAN.
